IRA H. SPENCER, OF HARTFORD, CONNECTICUT, ASSIGNOR TO THE SPENCER TURBINE CLEANER COMPANY, OF HARTFORD, CONNECTICUT, A CORPORATION OF CONNECTICUT.

CLEANING-TOOL.

1,016,649.

Specification of Letters Patent.

Patented Feb. 6, 1912.

Application filed June 9, 1908. Serial No. 437,529.

To all whom it may concern:

Be it known that I, IRA H. SPENCER, a citizen of the United States, and a resident of Hartford, in the county of Hartford and 5 State of Connecticut, have invented a new and Improved Cleaning-Tool, of which the following is a specification.

My invention relates to the class of devices specified, and the object of the invention is to provide a device of this class having numerous novel features of advantage 10 and utility. One form of device in the use of which this object may be attained is illustrated in the accompanying drawings, in 15 which—

Figure 1 is a view in section through the swiveled tool on plane denoted by line 1—1 of Fig. 2. Fig. 2 is a view in longitudinal section through the device on plane denoted 20 by line 2—2 of Fig. 1. Fig. 3 is a view similar to Fig. 2 but with the swiveled tool shown in a position reverse from that shown in Fig. 2.

In the accompanying drawings the number 5 denotes what I term the shank of the tool having a socket 6 within which the lower end of a handle 7 may be secured in any desired manner, it preferably, however, being removably secured in place. The 25 shank has its outer end 8 formed at an angle to that part adapted for attachment to the handle. This end may be formed at any desired angle to the shank, an angle of 135 degrees, however, preferably being used. A passage 9 is formed through the shank, 30 this passage terminating in an opening 10 formed through the side of the shank and having considerable length, this length preferably, however, not occupying more than 40 half the circumference of the shank. An end wall 11 is located within the shank, this wall gradually leading to the opening 10.

A body 12 is swiveled on the end of the shank, a spring ring 13 engaging grooves 45 within the shank and body, holding the parts in engagement while allowing free pivotal movement of the body upon the shank. This ring is of resilient construction and is sprung to place in a manner well-known to 50 devices of this class. The body 12 has upon one side a mouth 14 extending therethrough, this mouth being located in position to communicate with the opening 10 in one position of the body and forms an intake for the passage 55 of air and dust in the operation of the

tool. A buffer 15 is located about this mouth to prevent injury to articles of furniture or the like. On the opposite side of the body a brush is arranged, this in its construction including a base 16 to which the 60 bristles 17 are secured, and a mouth 18 extending therethrough into a chamber 19 from which a passage 20 extends and which is adapted to register with the opening 10 in the shank of the tool. 65

By reason of the angular position of the outer end of the shank with reference to the handle 7 and the free swiveled action of the tool base upon this end, the angle of the tool with respect to the axis of the handle 70 7 may be changed and controlled at will by simply turning the handle, which turning movement will cause the body of the tool to assume an angle to said axis, the end of the body on that side toward which the handle 75 is turned moving inward toward the handle and the opposite end moving outward therefrom.

The mouth 14 being placed upon the floor is adapted to take up dust, dirt and refuse 80 of various sorts, and from the construction it will be seen that when this mouth is placed upon the floor such mouth registers with the opening 10 to allow the passage of a current of air to carry such dust along the shank 85 and handle 7, it being understood that this device is adapted for use in a cleaning apparatus embodying a suction creating device.

When the brush is placed upon the floor 90 as shown in Fig. 3, its mouth registers with the opening 10 and the brush being used to stir up the dust, as is desirable in some cases, such dust and dirt are carried through the mouth 20 into the shank and along the handle to the apparatus creating the flow of air. 95

The tool is designed for such use that when either face is in its working position then only will the mouth of such working face communicate with the passage through the shank, and it is thus seen that the working position of the tool governs the inflow of air to the handle. 100

I claim:

1. A cleaning tool handle having a bent end with an opening therefrom located at 105 one side of the axial center of said bent end, the main part of the handle projecting away from said axis on the opposite side thereof from said opening, and a cleaning tool mounted to rotate upon the axis of said bent 110

end and having a plural number of cleaning faces each with an opening to register with said opening in the handle.

2. A cleaning tool handle having its end arranged at an angle to the main part and having a passage therein and an inlet opening and a long cleaning tool having oppositely disposed working faces extending lengthwise of the tool and arranged on opposite sides of the axis of said angular end, said tool being swiveled upon the end of the

handle upon an axis extending crosswise of the tool and between said working faces each of which has a mouth adapted to be brought into communication with said inlet on bringing either working face into working position. 15

IRA H. SPENCER.
